TRAFFIC SIGNAL

Gilbert W. Withers, Atlanta, Ga.

Application August 24, 1932. Serial No. 630,265

7 Claims. (Cl. 40—125)

This invention relates to traffic control, and more particularly to a new and improved traffic signal or marker for use on streets and highways.

5 Crowded living conditions, particularly in centers of population, coupled with a motor age, have made necessary intricate systems of traffic control. A considerable factor in connection with such systems is the traffic marker, which 10 usually consists of a plate or other indicating device anchored in the pavement or slab and bearing some such injunction as "Stop," "Slow," "Quiet," "School Zone," etc. Since to be effective these devices must appear more or less directly 15 in the line of traffic, they should be constructed as to give maximum visibility and yet at the same time provide minimum interference in the passage of vehicles thereover. A popular form of traffic marker is the solid rubber plate anchored 20 at right angles to the slab and over which traffic may pass with little inconvenience. An objection to this type of marker lies in the fact that the punishment it must take from traffic soon wears it out, and it must then be replaced in toto, even 25 though only one part has been damaged and the remainder of the plate is in good condition. Such replacement is both costly and wasteful. Further, since the entire length of the device is 30 exposed to oncoming traffic, and since contact with any part of said surface will rock or flatten the entire plate against the pavement, more wear than is necessary occurs because of this. Such contact causes at least some inconvenience to passengers in vehicles since the body of the 35 marker must impart some jar to an impacting automobile or the like, and, in addition, the marker furnishes a mental hazard to a driver, particularly a stranger, who, not knowing what the device is backed up by, and possibly having 40 had some experiences in hitting those of a solid type, may swerve into an adjoining lane of traffic in order to avoid hitting the marker, such action often resulting in serious accidents.

45 An object of this invention is to provide a traffic marker that may be quickly and easily replaced as to any of its working parts without the necessity of installing an entire new device.

Another object is to provide a marker which 50 will give greater visibility than the type now generally in use.

A still further object is to provide a marker, one part of which may be run over and flattened without any of the other parts being affected.

55 Another object is to provide a marker so constructed that a driver may easily avoid hitting it without swerving out of his line of traffic.

60 Summarized, the objects of this invention are to provide a marker that will be economical in construction and operation, efficient in its work-

ing, and highly effective for the purposes for which it is intended.

In order that my invention may be fully understood, reference is made to the drawing herein, in which:

Fig. 1 is a front elevational view of the device.

Fig. 2 is a top plan view of the marker illustrated in Fig. 1.

Fig. 3 is a front view of one of the letters forming part of the instant invention.

Fig. 4 is a view in vertical cross-section of the letter illustrated in Fig. 3.

Fig. 5 is a cross-section of the device shown in Fig. 2, taken along the line 5—5 thereof, looking in the direction of the arrows.

Referring to the construction in further detail, 10 designates the anchor plate or base member of my device, which member may be cast or otherwise suitably formed, and is preferably made of metal. It is intended that 10 shall be sunk flush to its top in the concrete, asphalt, or brick surface of the pavement, and in order to insure a particularly solid anchorage, the base may be formed with angles 11 at stated intervals, 15 said angles being carried to the top on the back of said base to form brackets 12, the function of which is made clear elsewhere herein.

The front of 10 is formed with a continuous over-hanging ledge 13, terminating in a flat base portion 14 (Fig. 5). A plurality of securing strips 15 are anchored on the rear of 10 by means of counter-sunk bolts 16 and washers 17, the base of 10 being drilled and threaded as at 18 to receive said bolts. The inner-bottom edge 20 of 15 is beveled as at 19, this structure cooperating with complementary formation 13 of the base to form a continuous open-topped triangular groove. The upper edge of 15 next said 25 groove may be slightly rounded as at 15a in order to preclude damage to the letters of the device by what might otherwise be a cutting edge at this point.

Special attention is now called to letters 20 of the marker. These letters are formed of rubber or rubber-fabric material, and the body thereof is preferably red in color and inlaid on a white background. The fabric construction insures upright position, and inlaying the letters guarantees that they will not wear off in the course of operation. A further reinforcing member in the shape of a metal T strip inserted in or near the bottom of the letter during the course of manufacture may be provided if desired, this member being indicated by the numeral 21 on the drawing. The base 22 of letter 20 is wedge-shaped, and made to conform to the triangular groove in base 10 previously described herein, it having been found desirable to construct this base slightly larger than the groove proper, such formation, in view of the elastic- 30

rubber composition of the letter, insuring a tight-fitting joint when the member is in place. The base 22 forms the foundation of the letter, the upper part of which may be fabricated so as to taper slightly towards its top, and the corners thereof may be fashioned with dog ears so as to prevent said corners from becoming ragged or unsightly in the course of time.

Between the letters in the base groove is a series of metal fillers or spacers 24, which members may be of cast metal and are shaped to conform exactly with the triangular groove referred to herein, the tops of said members terminating exactly with the top of base 10 and securing strips 15.

In operation, my device works as follows: Base 10 having been securely anchored in the pavement in a manner heretofore set out herein, letters 20 and fillers 24 are inserted from the rear, the letters and fillers entirely filling the triangular groove. Securing strips 15 are then put in place and fastened down by means of bolts 16, a further security of fixation being provided by the tops 12 of brackets 11 contacting and guiding said strips. In this manner the letters are firmly and securely held in place in exact spaced relationship.

It is to be noted that by removing one or more of the fillers, five, six, or seven letter words may be spelled on the same base, and exact spacing at the same time maintained, which factor of flexibility is of considerable convenience when changes are to be made. The desirability of a standard base which may be purchased in quantity lots and used for all markers of a municipal traffic system, is obvious.

When it becomes necessary to remove one of the letters because of its having become worn out or damaged, it is only necessary to remove one of strips 15 by loosening bolts 16, take out the old letter, substitute a new one in its place, and quickly restore the structure to its initial condition. This may be done at a small cost, both from the stand-point of material required and the time of the maintenance man who does the work. Tests have shown this operation may be performed, with the aid of a speed wrench, is less than one minute; while new letters may be procured for a relatively few cents as compared with the very considerable cost of replacing the entire indicating plate of the conventional marker.

I deem it desirable to make my base member possibly twice as long as that of the usual traffic marker, which construction gives the letters of the device a considerable spread, with attendant greater visibility to approaching traffic. When one of the letters is hit by the wheel of a vehicle, that letter alone is affected thereby, which fact is important both from a stand-point of wear on the device itself, and jar to the impacting member, it being apparent that the latter will be much less in the case of a single letter than when the entire device is upset, as happens with an ordinary marker. Further, a driver by merely turning the steering wheel a few inches may avoid the letter entirely and this without throwing his machine out of its traffic lane, which act is impossible in the case of a solid marker occupying a much greater continuous space. Thus it appears that the total wear on my device will be much less than upon the conventional type under the same traffic conditions, which fact is further significant both from a stand-point of maintenance and of yearly cost.

From the foregoing it is apparent that I have described a new and useful traffic signal which is efficient in operation, economical in construction, and thoroughly adapted to modern traffic and safety requirements. Without further explanation or elaboration, the foregoing will fully explain the essence of my invention, and others may, by applying current knowledge, readily adapt the same for use under various conditions without eliminating certain features which may be said to constitute the essential items of novelty herein, which items are intended to be defined and secured to me by the following claims.

I claim:

1. A traffic signal comprising a base, a beveled securing strip co-operating with said base, a portion of said base being so shaped as to form, with said strip, an open-topped triangular groove between the strip and base, flexible letters extending into said groove, and fillers between said letters in said groove. 90

2. A traffic marker comprising a metal base, anchoring brackets along the side of said base, securing strips associated with the top and rear of the base, a portion of said base being so shaped as to form with said strips a triangular groove therein, flexible letters extending into said groove, and filler members filling the space in the groove not occupied by the letters. 95 100

3. A traffic marker comprising a base, a series of anchoring brackets on one side of said base, the upper portions of said brackets forming guide members, securing strips associated with said base, said strips and base having portions so shaped as to co-operate to form an open-topped triangular groove, flexible letters having wedge-shaped bases extending into and filling said groove, and filler members in said groove between said letters. 105 110

4. A traffic signal comprising a base, a beveled securing strip co-operating with said base, a portion of said base being so shaped as to form with said strip an open-topped triangular groove, flexible letters associated with and filling said groove, filler members having wedge shaped bases extending into said groove, and means to unite the securing strip and the said base. 115 120

5. A traffic signal comprising a base, a securing strip co-operating with said base, a portion of said base being so shaped as to form with said strip an open-topped triangular groove between the strip and the base, rubber-fabric letters extending into said groove, filler members having wedge-shaped bases and terminating with the top of the base and securing strip, extending into said groove and entirely filling the space in the groove not occupied by the said letters. 125 130

6. A traffic signal comprising a base, a securing strip co-operating with said base, a portion of said base being so shaped as to form with said strip a groove between the strip and the base, said groove being wider at its bottom than at its top, and flexible letters extending into said groove, said letters being reinforced at their base with a T-shaped metal strip. 135 140

7. A traffic signal comprising a base, a securing strip co-operating with said base, a portion of said base being so shaped as to form with said strip a groove between the strip and the base, flexible letters extending into and filling said groove, and filler members likewise extending into said groove. 145
